UNITED STATES PATENT OFFICE

ED T. TROUT, OF CHILlicothe, TEXAS.

CHURN.

1,086,739.

Specification of Letters Patent. Patented Feb. 10, 1913.

Application filed August 2, 1913. Serial No. 782,735.

To all whom it may concern:

Be it known that I, ED T. TROUT, a citizen of the United States, residing at Chillicothe, in the county of Hardeman and State of Texas, have invented certain new and useful Improvements in Churns, of which the following is a specification, reference being had to the accompanying drawings.

This invention relates to new and useful improvements in churning and more particularly to a hand operated churn, the object of the invention being to provide a churn wherein the receptacle or body of the churn is rested upon the floor or platform and the operating mechanism thereof is suspended from a suitable support secured to the side of the wall or other suitable support.

Another object of the invention is to provide a churn of this character which will possess advantages in points of efficiency and durability, is inexpensive of manufacture and at the same time is simple in construction and operation.

With the above and other objects in view, this invention consists in the novel features of construction and the combination and arrangement of parts to be hereinafter more fully described, pointed out in the claims, and shown in the accompanying drawings,

in which—

Figure 1 is a front elevation, the churn body being shown in vertical section; Fig. 2 is a side elevation; Fig. 3 is a longitudinal sectional view of the connecting member 35 and the rotary blades; Fig. 4 is a transverse sectional view taken on the line 4—4 of Fig. 1; Fig. 5 is a top plan view of the upper agitator; Fig. 6 is a top plan view of the cover; and Fig. 7 is a sectional view taken on the line 7—7 of Fig. 1. Fig. 8 is a transverse sectional view taken through one of the agitator blades.

Referring more particularly to the drawings, 1 indicates the base plate which supports the bearing of my improved churn. Formed integral with the base and projecting outwardly at right angles thereto is the bearing member 2 which comprises the outwardly extending end members 3 and the central member 4 all of which are arranged in spaced parallel relation, as clearly illustrated in Fig. 2. The end pieces 3 are bifurcated to form the spaced arms 5 between which are rotatably mounted the gears 6, said gears being mounted upon each end of

the shaft 7, the intermediate portion of which is mounted in the central member 4.

A stub shaft 8 is rotatably mounted in the upper end of the central member 4 and mounted upon said stub shaft is a gear 9 having a handle member 10 whereby the same may be rotated, said gear engaging the gears 6 to impart motion thereto. The shaft 7 extends downwardly from the supporting member and into the cylindrical receptacle 11 to a point just above the bottom thereof. Formed integral with the lowermost gear 6 is a sleeve 12 which projects into an opening 13 formed in the upper end of the connecting member 14 and securely held therein by means of the set screw 15 whereby the bearing member may be quickly and readily removed from the sleeve, if desired.

Mounted upon the lower end of the shaft 7 is an agitator 15 which comprises an annular ring 16 to which are secured the outer ends of the blades 17, said blades being formed integral at their inner ends with a circular plate 18 which is mounted upon the lower end of the shaft 7 for rotation therewith. It will be noticed from the showing illustrated in Fig. 3 that the blades 17 are disposed at an angle with respect to the plate 18 so that upon the rotation of the agitator, the butter which is churned from the cream placed within the receptacle 11 will be forced toward the top thereof. Spaced supporting rods 19 are provided, the upper ends of which are rigidly secured within the lower end of the member 14 and the lower ends thereof suitably secured to the ring 20 which supports the second agitator 21. This agitator is constructed of a suitable ring 22 having the blades 23 secured at the outer ends thereof and their inner ends secured to the ring 20. It will be noticed that the blades in the second agitator are disposed at an incline opposite that in the first agitator 15 so that the two agitators apparently force the cream and butter toward each other whereby the cream will be more quickly churned into butter than by the churning in use at the present time.

A suitable cover 24 is provided which is arranged over the upper end of the receptacle 11 and securely held thereon by means of the thumb screws 25.

From the foregoing description taken in connection with the accompanying draw-

ings, it will be readily understood that I have provided a simple and durable churn, the operating mechanism of which is suitably suspended from the wall or other suitable support, while the receptacle thereof is arranged upon the floor or other support and adapted to receive the agitators which are rotatably mounted upon the operating mechanism. It will also be apparent that I have provided a new and useful churn which is extremely simple in construction, effective in its operation and can be manufactured at a comparatively low cost.

As clearly shown in Fig. 3, the blades of the agitators are each provided with the upwardly extending side flanges 26 which assist greatly in imparting motion to the cream within the receptacle. The upper edges of these flanges at their outer ends are flush with the ends of the rings and then taper inwardly toward the center support, as illustrated.

It is to be understood that my improved device may be easily attached to the wall; that the two agitators turning in opposite directions relative to each other will cause the butter to flow to the top; that any kind of a vessel or jar may be used for the body portion of the churn, either open or with a lid.

In order to reduce to a minimum the friction between the bearing journals and the rotating parts, it will be understood that ball bearings of the usual type may be applied to such parts in the manufacture of

the churns although the application of the aforesaid ball bearings is not disclosed in the accompanying drawings.

While I have shown and described the preferred form of my invention, it will be obvious that various changes in the details of construction and in the proportions may be resorted to for successfully carrying my invention into practice without sacrificing any of the novel features or departing from the scope of the appended claims.

What I claim is:-

1. A churn including agitators having blades disposed at an angle and upwardly extending flanges formed upon the longitudinal edges of said blades for imparting motion to the contents of the receptacle upon the rotation of the agitators.

2. A churn including agitators having angularly disposed blades, a ring connecting the outer ends of said blades, upwardly extending flanges formed upon the longitudinal edges of said blades, the upper edges of said flanges at their outer ends being flush with the upper edge of the rings and then tapered inwardly toward the central connecting member, as and for the purpose set forth.

In testimony whereof I hereunto affix my signature in the presence of two witnesses.

ED T. TROUT.
